DESIGN FOR A DRESS

Mary Porpora, New York, N. Y., assignor to
Franklin Simon & Co. Inc., New York, N. Y.

Application August 26, 1936, Serial No. 64,573

Term of patent 3½ years

To all whom it may concern:

Be it known that I, Mary Porpora, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The design is characterized by the nailhead embroidery as shown superimposed upon a contrasting background, in combination with the dress as shown. Said embroidery consists of a row of circular nailheads on the inner edge portion of the center slit facing and having a row of elliptical nailheads placed adjacent thereto, which ornamentation is repeated on the cuff portions of the dress.

I claim:

The ornamental design for a dress, substantially as shown and described.

MARY PORPORA.
